UNITED STATES PATENT OFFICE.

EDMUND RANKIN, OF LINCOLN, ILLINOIS.

SKIMMER FOR BOILERS.

1,363,269.

Specification of Letters Patent. Patented Dec. 28, 1920.

Application filed December 19, 1919. Serial No. 345,999.

To all whom it may concern:

Be it known that I, EDMUND RANKIN, a citizen of the United States of America, and a resident of Lincoln, county of Logan, and 5 State of Illinois, have invented certain new and useful Improvements in Skimmers for Boilers, of which the following is a full and clear specification.

This invention relates to devices for blowing off or removing scum, dirt, foam and sediment which rise to the surface of the water in steam boilers, and its object is to provide a novel and improved device of this kind which can be applied to locomotive and stationary bodies with equal facility, which has a large effective working area and in which the skimmer-tubes are so mounted that it remains perfectly level with the surface of the water in all positions of 20 the boiler.

The principal object of this invention is to provide a plurality of independent skimmer-tubes, each of which is automatically controlled by a separate float and has 25 a plurality of skimmer-nozzles extending in opposite directions relative to the float.

With the herein stated objects in view and others hereinafter set forth, the invention consists in a combination and arrangement of parts to be hereinafter described and claimed, reference being had to the accompanying drawings, in which—

Figure 1 is a side elevation of one arrangement of the improved skimming device mounted within a boiler;

Fig. 2 is a perspective view detached from the boiler;

Fig. 3 is a detail view showing a side elevation of one of the independent skimmers;

Fig. 4 is an end view of one of the skimmers and showing its normal position relative to the level of the water and also showing the circle of travel in dotted lines;

Fig. 5 is a sectional view through one of the skimmers and its float;

Fig. 6 is a sectional view showing a modified manner of constructing the skimmers;

Fig. 7 is a detail view showing one of the clamping sockets on the end of the pipe 50 frame.

Similar reference numerals in all of the figures of the drawings designate like parts.

Referring to the drawings, 10 designates an ordinary steam boiler, and 11 the fire-tubes thereof. Mounted within the boiler is the skimming apparatus, which comprises

a supporting-frame 12 for the skimmers formed of pipe-sections suitably connected together with elbows and T-joints, and said frame is rigidly supported parallel with the 60 axis of the boiler by vertical legs 13 which are provided with a clamping means at each end to engage and be fastened to said supporting-frame and the fire-tubes respectively. In the arrangement of parts shown 65 in the present instance, the supporting-frame 12 embodies a longitudinal central section 14, oppositely extending forward sections 15 projecting at right-angles to said central section 14, and parallel arranged 70 branch sections 16 extending from the rear end of the central section and parallel therewith. At its forward end, said pipe frame is connected to the top wall of the boiler by a vertical pipe 17 which extends through 75 the boiler wall to the outside of the boiler and has connected to it an outlet-extension 18 that is provided with a suitable blow-off-valve 19.

As shown in the drawings, each of the 80 pipe sections 14, 15 and 16 is provided with a skimmer device preferably formed of an integral casting having a hollow hub 20, two downwardly-extending and oppositely-curved pipe-arms 21 connecting with the 85 hollow hub, and an outwardly-extending nozzle 22 projecting from the lower extremity of each of the pipe-arms 21. Said hollow hub is pivotally mounted on a nipple 23 forming part of the supporting pipe-frame and said nipple is provided with apertures 24 communicating with the pocket or hollow formed in the hub, and said hub is retained in position by collar socket members 25 which are movably secured to nipple 23 in any suitable manner and the socket portion of which engages around short tubular extension 26 formed on opposite sides of the hub.

The skimmers are buoyantly supported in 100 the water of the boiler with the nozzles 22 positioned slightly below the surface of the water by floats 27 which are removably fixed to the skimmers in any suitable manner and position between the pipe-arms 21 and approximately on the center line of the hub 20 and the axes of the nozzles 22.

With the construction thus described, it is obvious that each skimmer can rise and fall independently of each other and has a 110 radius of action equal to the distance between the axis of the hub and the axis of

the nozzles, and can move in a complete circle about the axis of the hub.

In the modified form shown in Fig. 6 of the drawing, the hub 28 is cast with a central socket 29 to which the float-ball is secured, and two side sockets 30 in which pipe-arms 31 are secured.

In operation, when the blow-off-valve 19 is opened, the pressure within the boiler 10 will force the scum, dirt or foam into the nozzles 22 through the pipe-arms 21 into the hubs 20; then through apertures 24 into the pipe-frame; and through the pipe-frame and pipe 17 to pipe 18 and out of the discharge-end.

The free ends of each of the skimmer supporting sections 15 and 16 are closed by a cap 32, each of said caps being provided with a blow-out orifice 33, so that, when 20 valve 19 is opened, the steam pressure will enter the pipe-frame through the openings 33 and force out any sediment which might accumulate in the terminals of the pipe-frame beyond the outlet apertures 24, thus 25 avoiding any dead ends in the apparatus.

One advantage of using a plurality of separate and independently-pivoted skimmers is that the skimmers can be made relatively small and of light weight, thereby 30 requiring relatively small floats which will allow the skimmer-nozzles to skim close to the fire-tubes, or to the bottom of the drums in water-tube boilers, and the water in the boiler will not have the same force on the 35 small float as on a large one, nor will the pressure crunch them as easily as it would a large one.

By forming the pipe-frame of connected sections of pipe, it is possible to form as 40 many skimmer supporting branches as is necessary to cover the water-surface area of any design of boiler. In a large boiler, the skimmers should be widely scattered. In a small boiler, they could be radially arranged around an outlet-pipe similar to pipe 45 17; and in a locomotive boiler they should be placed on each side of the dry-pipe, the number of skimmers to be used depending upon the size of the boiler.

50 It will be observed that the skimmers can be mounted to swing transversely or longitudinally of the boiler, and are as effective in one position as in the other position.

The skimmers being independent of each 55 other, they are not affected generally when the water is boiling high under one or more of them and are free to drop in the low eddies formed by accumulated dirt and foam and will not be raised together with those 60 which are being affected by the high boiling water. A further advantage is the submergence of the nozzles or intake-tubes. This locates them in clear water and consequently prevents the nozzles being clogged 65 with dirt, and when the blow-off-valve is

opened the pressure of steam seeking to escape through the nozzles creates an inrush or funnel-shaped suction which will rapidly clear the surface of the water of the dirt and foam and with the use of less steam than usual.

The nature and scope of the invention having been thus indicated and its preferred embodiment having been specifically described, what is claimed as new is:

1. A boiler cleaner comprising a pipe-frame rigidly supported in the boiler and forming a discharge-conduit, a blow-off-valve for said discharge-conduit, and a plurality of float-controlled skimmers pivoted 80 axially and separately on said pipe-frame and mounted in communication therewith, whereby they can operate independently of each other.

2. A boiler cleaner comprising a pipe-frame rigidly supported in the boiler and forming a discharge-conduit, a blow-off-valve for said discharge-conduit, and a plurality of float-controlled skimmers pivoted 90 separately on said pipe-frame and mounted in communication therewith, each of said skimmers being formed with a hollow hub in communication with the pipe-frame, pipe-arms extending from said hub and provided with laterally-projecting nozzles, and a float 95 mounted between the pipe-arms.

3. A boiler cleaner comprising a pipe-frame forming a discharge-conduit, means for removably and rigidly supporting it upon the tubes within a boiler, a blow-off-valve for said discharge-conduit, a plurality of skimmers in communication with said discharge-conduit and pivoted axially and separately thereon, each of said skimmers being provided with a float and laterally-extending nozzles.

4. In a boiler cleaner, a fixed discharge-conduit, a blow-off-valve therefor, a plurality of skimmers pivoted on said discharge-conduit and in communication therewith, and means for retaining each of said skimmers in position, embodying a pivoted hub and a pair of collar sockets constructed to engage opposite sides of the pivoting hub and provided with means for detachably securing them to said discharge-conduit.

5. In a boiler cleaner, a fixed discharge-conduit formed of sections of pipe, elbow and T-joints detachably connected together, 120 whereby said discharge-pipe can be formed with numerous branch conduit extensions projecting laterally therefrom at different angles, and a float-controlled skimmer pivoted axially on each of said branch extensions and communicating therewith.

6. In a boiler cleaner, a fixed discharge-conduit supported in the steam space of a boiler, a float-controlled skimmer pivoted adjacent the end of said conduit, said skim-

mer being provided with a hollow hub communicating with said discharge-conduit and which forms the pivoting means for the skimmer, a closing-cap for the end of the discharge-conduit, said cap being provided with a relatively small aperture forming a blow-hole between the steam space of the boiler and the interior of the discharge-conduit, whereby accumulation of dirt in

the extreme end of the discharge-conduit is 10 eliminated.

In testimony whereof I hereunto affix my signature.

EDMUND RANKIN.
